HINGE

Maud L. Anderson, Aurora, Ill.

Application September 9, 1939, Serial No. 294,054

5 Claims. (Cl. 16—135)

This invention relates to concealed hinges, particularly adapted, though not necessarily limited in its use for hanging automobile doors, and one of the objects of the invention is to provide an improved hinge of this character comprising a very small number of parts, preferably four, such parts being so constructed that when assembled the door member will strengthen and reinforce the pillar member, thereby maintaining the structure against collapsing and the parts against displacement, relatively one with respect to the other to prevent binding of the parts, and thereby insure a free and easy operation of the hinge.

To the attainment of these ends and the accomplishment of other new and useful objects as will appear, the invention consists in the features of novelty in substantially the construction, combination and arrangement of the several parts, hereinafter more fully described and claimed and shown in the accompanying drawing illustrating this invention, and in which

Figure 1 is a perspective view of a hinge of this character constructed in accordance with the principles of this invention and showing the parts in an open position with respect to each other.

Figure 2 is a detail perspective view of a casing forming a part of the hinge.

Figure 3 is a detail perspective view of the door member of the hinge.

Figures 4 and 5 are detail perspective views, partly broken away, of the elements constituting the pillar member.

Figure 6 is a sectional view taken on line 6—6, Figure 1, showing in dotted lines the hinge member in a closed or folded position.

Figure 7 is a detail sectional view taken on line 7—7 Figure 6.

Figure 8 is a detail perspective view of a portion of a modified form of door member.

Figure 9 is a detail sectional view of a modified form of one of the elements of the pillar member.

Figure 10 is a plan view of a portion of one of the elements of the pillar member shown in Figures 4 and 5.

The hinge consists essentially of a door member designated generally by the reference character D and a pillar member comprising separate elements 10 and 11. The elements 10—11 are preferably of L-shaped configuration to form respectively portions 12 and 13 having openings 14 therethrough by means of which they may be anchored to the pillar of a door frame.

These elements 12 and 13 constitute brackets having portions 15 between which the door member is pivotally mounted. Each of the members

15 is of a substantial thickness, being provided with an opening 16 therethrough at one corner thereof and is recessed to provide a bearing surface or shoulder 17 described from the center or axis of the opening, the radius of the recessed portion being greater than the radius of said opening.

An arcuate groove 18 is provided in the member 15 and is described from the same center or point, to provide abutting or bearing surfaces or shoulders 19—20, the ends of the groove being preferably open.

The door member D comprises an anchor plate 21 having apertures 22 by means of which it may be anchored or secured to a door, and supported by the plate is an arm comprising portions 23 and 24 arranged at substantially right angles to each other, one end of the arm being anchored to the plate 21, and at the other end of the arm, trunnions or pins 25 are provided which constitute the pivot pin for pivotally connecting the door member with the pillar elements. Encompassing the pivot pin 25 are shoulders 26 of a diameter considerably greater than the diameter of the pivot pin, so that when the ends of the pivot pin 25 are inserted in the aperture 16 of the respective pillar elements, the periphery of the shouldered portion 26 will contact the bearing surface or shoulder 17 of the pillar element, as shown more clearly in Figure 7 of the drawing.

Projecting from the edges of the arm of the door member are arcuate extensions 27 described from the center or axis of the trunnions 25, each having a surface 28 that is adapted to engage and move against the bearing surface 19 of the respective elements of the pillar member.

In order to hold the parts in assembled relation there may be provided a casing 29 into which the portions 15 of the pillar elements together with the pivot end of the arm of the door member are adapted to be inserted, the casing forming a housing for these parts.

This housing may be secured against removal in any desired or suitable manner preferably by spot welding. The free edge of the wall 30 of the housing 29 preferably terminates short of the plane of the free edge 31 of the opposite wall, so that the edge of the wall 30 will form a stop against which the arm of the door member contacts to limit the movement of the door member with respect to the pillar member in one direction.

With this construction it will be noted that the surfaces 17 and 19 of the elements of the pillar member are struck or described from the center or axis of the opening 16 which receives the pivot pin.

25, so that when the parts are assembled and the surface 28 contacts the surface 19, and the periphery of the shoulder 26 contacts with the bearing surface 17, all stress or strain upon the pivot 5 pins 25 will be relieved, by reason of the contact of the surfaces 28 with the bearing surfaces 19, and of the periphery of the shoulder 26 with the surface 17.

At the same time these bearing surfaces, being 10 described upon the same arc, will provide a free swinging movement of the door member with respect to the pillar member.

The shoulder 26 contacts a surface 32 which surrounds the aperture 16 in which the pivot pin 15 25 is journaled, and serves the function of maintaining the elements of the pillar member in their proper spaced relative positions, so that the elements of the pillar member will be maintained against collapsing and binding upon the pivot 20 pins 25. The elements of the pillar member are maintained in assembled relation with respect to the door member by reason of the casing or housing 29.

The form of the invention shown in Figures 8 25 and 9 operates in the same manner with the exception that in the edges of the arm 24 of the door member there is provided an arcuate groove 33 to form a shoulder or surface 34. A boss 35 is also provided on the arm 24 to form a bearing 30 surface 36, and this boss is provided with a recess or seat 37 opening through the end thereof to receive a trunnion or projection 38 on the element 39 of the pillar member. This projection 38 is preferably substantially flush with the face 35 40 of the element 39, and encompassing the projection 38 is a recess 41 into which recess the boss 35 is adapted to be seated when the projection 38 is seated in the recess 37. A projection 42 carried by the element 39 extending at substantially right angles thereto operate in the groove 33 so as to contact the surface 34, and if desired the opposite face 43 of the groove 33 may form a bearing surface for the opposite face of the projection 42.

45 By forming the periphery 36 of the boss 35 and the walls 34 and 43 of the groove 33 on arcs all described from the center of the recess or seat 37, it will be manifest that the parts will be reinforced and braced while at the same time their free movement will not be impaired.

50 The free end of the boss 35 which is seated in the recess 41 contacting with the base of the recess will also serve as a means for preventing the parts from being displaced, which would result 55 in a binding action of the hinge.

With this improved construction it will be manifest that there is provided a hinge which is constructed of a minimum number of parts, preferably four in number, and when the parts are 60 assembled there will be provided a strong and effective hinge which will, when in use, be concealed and at the same time permit the door in connection with which it is used, to swing outwardly, away from the pillar and out of the way.

65 While the preferred forms of the invention have been herein shown and described, it is to be understood that various changes may be made in the details of construction, and in the combination and arrangement of the several parts, 70 within the scope of the claims, without departing from the spirit of this invention.

What is claimed as new is:

1. A hinge comprising a pair of relatively movable hinge elements, one of said elements comprising independent members spaced from each

other and each having a bearing opening and a bearing surface partially encompassing said opening, said surface being formed on a substantially greater radius than that of said opening and being described from the center of the opening, the other element of the hinge comprising an arm movable between said spaced members, pintles integral with and projecting from opposite edges of said arm, a portion of the periphery of each of the pintles forming a bearing surface 10 to contact the respective first said bearing surfaces, another portion of each of the pintles being reduced in diameter to form a trunnion entering the said respective openings, the said spaced members of the hinge and the said arm 15 being provided one with grooves struck from the centers of said openings, and the other with integral projections entering and moving in the respective grooves.

2. A hinge comprising a pair of relatively movable hinge elements, one of said elements comprising independent members spaced from each other and each having a bearing opening and a bearing surface partially encompassing said opening, said surface being formed on a substantially greater radius than that of said opening and being described from the center of the opening, the other element of the hinge comprising an arm movable between said spaced members, pintles integral with and projecting from opposite 20 edges of said arm, a portion of the periphery of each of the pintles forming a bearing surface to contact the respective first said bearing surfaces, another portion of each of the pintles being reduced in diameter to form a trunnion entering 25 the said respective openings, the said spaced members of the hinge and the said arm being provided one with grooves struck from the centers of said openings, and the other with integral projections entering and moving in the respective 30 grooves, the said integral projections being of 35 substantial length each having a surface forming an arc struck on a radius described from the centers of the respective pintles.

3. A hinge comprising a pair of relatively movable hinge elements, one of said elements comprising independent members spaced from each other and each having a bearing opening and a bearing surface partially encompassing said opening, said surface being formed on a substantially greater radius than that of said opening and being described from the center of the opening, the other element of the hinge comprising an arm movable between said spaced members, pintles integral with and projecting 45 from opposite edges of said arm, a portion of the periphery of each of the pintles forming a bearing surface to contact the respective first said bearing surfaces, another portion of each of the pintles being reduced in diameter to form a trunnion entering the said respective openings, the said spaced members of the hinge and the said arm being provided one with grooves struck from the centers of said openings, and the other with integral 50 projections entering and moving in the respective grooves, the said integral projections being of substantial length each having a surface forming an arc struck on a radius described from the centers of the respective pintles.

4. A hinge comprising a pair of relatively movable hinge elements, one of said elements comprising independent members spaced from each other and each having a bearing opening and a bearing surface partially encompassing said opening, said surface being formed on a substantially greater radius than that of said opening 70 and being described from the center of the opening, the other element of the hinge comprising an arm movable between said spaced members, pintles integral with and projecting from opposite edges of said arm, a portion of the periphery of each of the pintles forming a bearing surface to contact the respective first said bearing surfaces, another portion of each of the pintles being reduced in diameter to form a trunnion entering the said respective openings, the said spaced members of the hinge and the said arm being provided one with grooves struck from the centers of said openings, and the other with integral 75 projections entering and moving in the respective grooves, and a housing for maintaining said spaced members in assembled relation and into which housing the said arm is movable.

- ing and being described from the center of the opening, the other element of the hinge comprising an arm movable between said spaced members, pintles integral with and projecting from opposite edges of said arm, a portion of the periphery of each of the pintles forming a bearing surface to contact the respective first said bearing surfaces, another portion of each of the pintles being reduced in diameter to form a trunnion, and a shoulder at the base of said trunnion, said trunnions entering the respective said openings and said shoulders engaging the proximate face of the respective said spaced members for maintaining them in fixed spaced relation, the said spaced members of the hinge and the said arm being provided one with grooves struck from the centers of said openings, and the other with integral projections entering and moving in the respective grooves.
5. A hinge comprising a pair of relatively movable hinge elements, one of said elements comprising independent members spaced from each other and each having a bearing opening and a bearing surface partially encompassing said opening, said surface being formed on a substantially greater radius than that of said opening and being described from the center of the opening, the other element of the hinge comprising 5 an arm movable between said spaced members, pintles integral with and projecting from opposite edges of said arm, a portion of the periphery of each of the pintles forming a bearing surface to contact the respective first said bearing surfaces, another portion of each of the pintles being reduced in diameter to form a trunnion entering the said respective openings, the said spaced members of the hinge and the said arm being provided one with grooves struck from the 10 centers of said openings, and the other with integral projections entering and moving in the respective grooves, a portion of the periphery of said pintles coinciding with the outer face of that portion of said spaced members in which the 15 openings for the said trunnions are arranged.
20. 5. A hinge comprising a pair of relatively movable hinge elements, one of said elements comprising independent members spaced from each other and each having a bearing opening and a
